Patented Apr. 27, 1926.

UNITED STATES PATENT OFFICE.

JOHN W. BLEASDALE, OF JANEVILLE, WISCONSIN.

TYING MACHINE.

Application filed September 26, 1924. Serial No. 740,054.

To all whom it may concern:

Be it known that I, JOHN W. BLEASDALE, a citizen of the United States, residing at Janesville, in the county of Rock and State 5 of Wisconsin, have invented certain new and useful Improvements in Tying Machines, of which the following is a specification.

This invention relates to a tying machine, designed primarily for use in connection with the tying of tobacco hands, but it is to be understood that a machine in accordance with this invention is adapted for any purposes for which it is found applicable, and the invention has for its object to provide, in a manner as hereinafter set forth, a machine of the class referred to for expeditiously tying hands of tobacco with twine.

The invention further aims to provide a machine for tying tobacco hands with 20 twine, and having means for holding the leaves of the hand, tucking a loop under the twine band, cutting the twine and releasing the hand when tied and whereby such functions will be quickly and efficiently performed without injury to the leaves.

Further objects of the invention are to provide, in a manner as hereinafter set forth, a machine for tying tobacco hands with twine, which is simple in its construction 30 and arrangement, strong, durable, compact, thoroughly efficient and convenient in its use, readily assembled, and comparatively inexpensive to set up.

With the foregoing and other objects in view the invention consists of the novel construction, combination and arrangement of parts, as hereinafter more specifically described and illustrated in the accompanying drawings, wherein is shown an embodiment 40 of the invention, but it is to be understood that changes, variations and modifications can be resorted to which fall within the scope of the claims hereunto appended.

In the drawings wherein like reference 45 characters denote corresponding parts throughout the several views:—

Figure 1, is a top plan view of a tying machine showing a hand tied with twine.

Figure 2, is a front elevation, broken 50 away.

Figure 3, is a fragmentary view, in horizontal section, illustrating the clamp, tuck forming needle, twine guide, and cutter.

Figure 4, is a section on line 4—4, Fig- 55 ure 3.

Figure 5, is a section on line 5—5, Figure 3.

Figure 6, is a section on line 6—6, Figure 3.

Figure 7, is a section on line 7—7, Figure 60 4.

Figure 8, is a section on line 8—8, Figure 3.

Figure 9, is a perspective view illustrating the holder, clamp, guide, and the housing 65 for the needle and cutter.

Figure 10, is a plan illustrating a hand and the string in full lines prior to the operation of the tucking needle, and in dotted lines the position of the tucking needle and 70 twine as the needle moves inwardly to tuck the twine.

Figure 11, is a plan illustrating a hand tied with twine.

Figure 12, is a sectional view of a hand 75 showing the position of the twine when secured to one end of the hand.

Figure 13, is a perspective of a tobacco hand tied with twine.

Referring to the drawings in detail 1 denotes a platform having a flanged plate 2 secured to the upper face thereof. The flange of the plate 2, is at the inner side thereof and indicated at 3, and which is positioned between the transverse center and one end 80 of the platform 1. The plate 2 projects forwardly of the platform 1, as at 4 and has a portion of its forward edge inclining rearwardly, as at 5 and terminating at the flange 3.

Connected to the lower face of the platform 1, at each side thereof, as well as projecting forwardly therefrom is a pair of substantially wide supports 6, 7. A frame 8, for supporting the platform 1, is secured 85 to the supports 6, 7.

Mounted on the supports 6, 7, as well as being secured thereto is a flat bar 9, having the part 10 thereof of less width than the part 11. The part 10 is spaced from the platform 1, and the part 11 extends under a portion of the forward end of the plate 2. The part 10 in proximity to its free end, has its upper face formed with a transverse extension 12 which provides a pair of shoulders 13, 14. The part 11 in proximity to its inner end has a transverse groove 15, in its upper face. The part 10 is also provided with a lengthwise extending slot 16 in the inner portion thereof.

The machine further includes a housing for what may be termed a combined twine tucker and cutter mechanism, the latter will be hereinafter referred to, but with respect to the housing it comprises a top wall 17, a pair of side walls 18, 19 and a pair of end walls 20, 21. The end walls are of less height than the side walls and the side walls are secured to the part 10 of the bar 9. The end wall 20 is flanged at its lower end, as at 22, and such flange is secured to the part 10, of the bar 9, by the holdfast devices 23. The end wall 20 abuts against the shoulder 13. The end wall 21 seats on the inner end of the part 11, of the bar 9 and is inclined in an outward direction with respect to the top wall 17. The holdfast devices for securing the side walls to the part 10, of the bar 9, are indicated at 24. See Figure 8. The end wall 21 is formed centrally thereof with a rectangular opening 25 and further formed in proximity to the side wall 19 with a rectangular slot 26. The purpose of the opening 25 and slot 26 will be presently referred to.

The side wall 19, at its inner end, is provided with an integral extension 27 formed with a vertically disposed wing 28, which is spaced from the end wall 21 to form a notch 29 for the passage of the twine 30. The extension 27 is also formed with a wing 31, disposed at right angles with respect to the wing 28 and seated in the upper face of the part 11 of the bar 9. The wing 31 is disposed transversely with respect to the part 11 and the free end of said wing constitutes an abutment for the hinge or pivoted end of a clamp to be hereinafter referred to. The extension 27 is of a length to be positioned against the forward side of the part 11 of the bar 9. See Figure 2. The function of the wing 28 will be presently referred to.

Forwardly of the plate 2 a hand holder 45 is arranged and which is constructed of a piece of bendable sheet metal and comprises a body portion 32, an upwardly extending and rearwardly inclined flange 33, and a downwardly extending vertically disposed flange 34. The body portion 32 is positioned on the upper face of the part 11, of the bar 9, and secured therewith by the holdfast devices 35. The lower portion of the flange 34 is positioned against the forward edge of the part 11, of the bar 9, and is secured thereto by the holdfast devices 36. The body portion 32 abuts against and forms a continuation of the plate 2. The holder which is referred to generally by the reference character 37 extends from the outer end of the part 11, of the bar 9, and terminates at the outer side wall of the groove 15. See Figure 3.

Arranged forwardly of the plate 2, and spaced from the holder 37, by the groove 15,

is a guide element referred to generally by the reference character 38 and which is spaced from the lower end of the end wall 21. The guide element 38 consists of a base 39, secured to the upper faces of the part 11, of the bar 9, by the holdfast devices 40. That end of the base 39, which opposes the end wall 21 of the housing, has formed integral therewith a vertically disposed inverted substantially L-shaped twine guide 41 having its free end torsionally curved, as at 42.

The base 39 is of less width than the part 11, of the bar 9, and terminates at a point removed from the forward edge of said part 11. The twine guide 41 is of the same width as the width of the base 39 and has formed integral with the forward side thereof, as well as extending at right angles with respect thereto, a vertically disposed wing 43, which opposes the wing 28, and in connection with the latter provides a cutter guide. The wing 43 is spaced from the wing 28 and the guide passage 44, formed by the wing 28 and 43 opposes the slot 26, in the wall 21.

The twine guide acts as a guide for the tucking needle, as said guide includes a vertical leg 45, a horizontally disposed leg 46 and a depending extension 47 on the free end of the leg 46. The extension opposes the leg 45 and the inner edge of the extension and leg is arranged in alignment with the opening 25 formed in the end wall 21 of the housing and the extension 47, in connection with the leg 45 provides a passage 48. The twine tucking needle which will be presently referred to, when it travels to and from in operative position, it is compelled to pass to one side of the leg 45. See Figure 6.

Interposed between the guide element 38 and the holder 37 is a clamping member employed for clamping the hand of tobacco against the holder and the wing 43 during the tying operation and said clamping member is arranged within and projected rearwardly from the groove 15 and extends upon the plate 2, when in normal position. See Figure 6. The clamping member is constructed from a strip of spring metal bent upon itself to provide a base 49 and a curved arm 50. The base 49 has its rear part offset as at 51 and which terminates in the bend 52. The offsetting of the base 49 permits of the rear portion of the clamp to extend upon the plate 2. The forward end of the base 49, is bent to form a barrel 53, which seats in a semi-circular depression 54 formed in the bottom of the groove 15. Extending through the barrel 53 and secured in position by the holder 37 and guide element 38 is a pintle 55, which in connection with the barrel 53, provides a hinge connection for the clamping member. The wing 31, of the

extension 27 abuts against the barrel 43. The forward or free end of the arm 50, of the clamping member, is curved upwardly as at 56.

- 5 The combined twine tucker and cutter mechanism comprises a spring controlled plunger 57 having projecting from its rear end a stem 58 which slides on the part 10 of the bar 9, and has its rearward movement 10 arrested by the shoulder 14. The controlling spring for the plunger 57 as indicated at 59, is arranged above the stem 58, and has one end connected as at 60 to the plunger 57 and its other end attached to an anchoring member 61, which is secured to the extension 12. The plunger 57 rides against the inner face of the top 16 of the housing and is confined in its movement by said top 17 and the part 10, of the bar 9. The forward end of the 20 plunger 57 is bevelled as at 62 to conform to the inclination of the end wall 21 of the housing.

Secured in the plunger 57, as well as projecting from the forward end of the plunger 57, centrally thereof, is the shank 62 of a twine tucking needle 63. The shank 62 and the needle point are constructed in such manner relative to each other so as to set up a twine shifting shoulder 64. The needle 30 operates through the opening 25, in the end wall 21 of the housing. See Figure 3. One side of the plunger 57 is mortised, as at 65 and mounted therein is a twine cutter 66. Holdfast devices 67 are employed for fixedly securing the cutter to the plunger 57. The cutter 66 projects forwardly from the plunger 57, but the projecting portion thereof is of materially less length than the projecting portion of the shank of the needle 63, and by this arrangement the needle will 40 perform its tucking function before the twine is severed by the cutter or in other words the needle operates in advance of the cutter. The cutter operates through the 45 slot 26 and enters the guide passage 44. See Figure 4. During the operation of the cutter it slides against the side wall 19 of the housing.

Pivottally connected as at 68 to a support 50 70, arranged below the platform 1, is a foot treadle 71, to which is connected as at 72, the lower end of a flexible cable 73, which travels over a pulley 74, carried by a bracket 75, secured to the lower face of the bar 9. The upper end of the cable 73 is provided 55 with a hook 76, for engagement in an eyebolt 77, which is secured to and depends from the plunger 57. When the treadle is depressed, owing to the connection of the cable 73, with the plunger 57, the latter is shifted forwardly against the action of the spring 59, and when the treadle 71 is relieved of pressure, the spring 59 will restore the plunger 57 to its normal position.

65 Mounted on the platform 1 is a receptacle

77, which contains a ball of twine 78. The receptacle 77 is provided with a cover 79, formed with an opening 80 for the passage of the twine 80 and the latter extends between the wing 28 and the end wall 21 of the housing. See Figure 2.

The operation of tying the hand of tobacco is as follows:—

The tobacco leaves are gathered together in the left hand, the thumb resting at a point 75 where the band is to be placed. The twine is held between the thumb and finger of the right hand and the end of the twine, is placed under the thumb of the left hand, then wind the twine firmly around the leaves using the 80 thumb of the left hand as a guide for the first lap. After the twine has been firmly wound around one end of the hand of tobacco, it is thrown over the torsionally twisted portion of the twine guide and simultaneously the hand of tobacco is pressed against the bottom and flange of the holder, with the stem end of the hand of tobacco held firmly against the twine guide. At this time 85 a finger is placed under the upraised end of 90 the clamp, which has been automatically elevated by the positioning of the hand of tobacco and the finger is used to shift the clamp in a direction towards the flange of the holder to firmly hold the hand of tobacco. The twine is then drawn across the needle until taut, after which, the foot tread is operated and at the same time the tension of the thumb and finger is simultaneously eased to permit of the twine to be tucked in 95 100 the hand of tobacco and then cut by the combined tucking and cutter mechanism. After which the foot lever is released, and the free end of the twine is pulled taut, so that it appears as shown in Figures 12 and 13.

It is thought that the many advantages of a tying machine in accordance with this invention, for use in connection with hands of tobacco can be readily understood, and although the preferred embodiment of the 105 invention is as illustrated and described, yet changes in the details of construction can be had which will fall within the scope of the invention as claimed.

What I claim is:

1. A machine for tying a tobacco hand with twine comprising means for tucking into one end of a tobacco hand a length of twine extended from a band of twine surrounding said end, and means for cutting the twine to free the band and the tucked length of twine, a holder for the hand of tobacco, a hand clamping member cooperating with said holder, and guides for said tucking and cutting means.

2. A machine for tying a tobacco hand with twine comprising means for tucking into one end of a tobacco hand a length of twine extended from a band of twine surrounding said end, and means for cutting

- the twine to free the band and the tucked length of twine, and guides for the said length of twine and tucking and cutting means.
5. 3. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine.
10. 4. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a holder for the hand of tobacco, and a hand clamping member cooperating with said holder.
15. 5. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a holder for the hand of tobacco, a hand clamping member cooperating with said holder, a guide for the length of twine, and guides for the tucking and cutting means of said mechanism.
20. 6. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a flanged holder for the hand of tobacco, and a clamping member coacting with the flange of the holder to clamp the hand during the tucking and cutting operation.
25. 7. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, and guides for the tucking and cutting means of said mechanism.
30. 8. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a flanged holder for the hand of tobacco, and a clamping member coacting with the flange of the holder to clamp the hand during the tucking and cutting operation, and guides for the tucking and cutting means of said mechanism.
35. 9. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a guide for the length of twine, and guides for the tucking and cutting means of said mechanism.
40. 10. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a holder for the hand of tobacco, a hand clamping member cooperating with said holder, a guide for the length of twine, and guides for the tucking and cutting means of said mechanism.
45. 11. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a flanged holder for the hand of tobacco, and a clamping member coacting with the flange of the holder to clamp the hand during the tucking and cutting operation, a guide for the length of twine, and guides for the tucking and cutting means of said mechanism.
50. 12. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a holder for the hand of tobacco, a hand clamping member cooperating with said holder, and said clamping member interposed between said guides and holder.
55. 13. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a flanged holder for the hand of tobacco, and a clamping member coacting with the flange of the holder to clamp the hand during the tucking and cutting operation, and said clamping

member interposed between said guides and holder.

14. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a holder for the hand of tobacco, a hand clamping member cooperating with said holder, guides for the tucking and cutting means of said mechanism, and said clamping member interposed between said guides and holder.

15. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a flanged holder for the hand of tobacco, a clamping member coacting with the flange of the holder to clamp the hand during the tucking and cutting operation, guides for the tucking and cutting means of said mechanism, and said clamping member interposed between said guides and holder.

16. A machine for tying tobacco hands with twine comprising a combined spring controlled twine tucker and cutting mechanism for successively tucking into one end of a tobacco hand a length of twine extended from a band of twine surrounding said end and for cutting the twine to free

the band and tucked length of twine, a holder for the hand of tobacco, a hand clamping member cooperating with said holder, a guide for the length of twine, guides for the tucking and cutting means of said mechanism, and said clamping members interposed between said guides and holder.

17. A machine for tying tobacco hands with twine comprising a combined spring controlled twine tucker and cutting mechanism for successively tucking into one end of a tobacco hand a length of twine extended from a band of twine surrounding said end and for cutting the twine to free the band and tucked length of twine, a flanged holder for the hand of tobacco, and a clamping member coacting with the flange of the holder to clamp the hand during the tucking and cutting operation, a guide for the length of twine, guides for the tucking and cutting means of said mechanism, and said clamping members interposed between said guides and holder.

18. A machine for tying a tobacco hand with twine comprising means for tucking into one end of a tobacco hand a length of twine extended from a band of twine surrounding said end, and means for cutting the twine to free the band and the tucked length of twine, a holder for the hand of tobacco, a hand clamping member cooperating with said holder, guides for said tucking and cutting means, and said clamping member interposed between said guides and holder.

In testimony whereof, I affix my signature hereto.

JOHN W. BLEASDALE.
